UNITED STATES PATENT OFFICE.

FELIX KRAEMER, OF NEW YORK, N. Y.

DESIGN FOR THE FRONT OF PIANO-COVER.

SPECIFICATION forming part of Design No. 18,061, dated February 14, 1888.

Application filed January 3, 1888. Serial No. 259,748. Term of patent 7 years.

To all whom it may concern:

Be it known that I, FELIX KRAEMER, of the city, county, and State of New York, have invented a new and original Design for Front of 5 Upright-Piano Covers, of which the following is a specification.

The invention relates to a design for the fronts of covers or scarfs of upright pianos; and the design consists of a cover or scarf with 10 one or more pictures on the front of said cover and ornamental borders around said pictures.

The nature of my design is fully shown in the accompanying drawings, in which—

Figure 1 represents a perspective view of a 15 cover or scarf for upright pianos made according to my design; and Fig. 2 is a detail front view of a portion of the same, drawn on a larger scale.

Similar letters of reference indicate corresponding parts.

In the drawings, A represents a cover or scarf for upright pianos, and B is the front piece of the same.

C represents one or more pictures of com- 25 posers or artists on said front.

D are ornamented borders for said pictures, and d tassels, rosettes, or other ornaments at the corners of said borders. The pictures form an appropriate and artistic ornamentation for covers of this class, and render the 30 same more attractive.

E are embroidered ornaments arranged at the sides of the picture.

Having thus described my design, I claim as new and desire to secure by Letters Patent— 35

The design for the front of piano-covers, consisting of a picture on said front, an ornamental border around said picture, and ornaments at both sides of said picture, substantially as shown and described. 40

In testimony that I claim the foregoing as my invention I have signed my name in presence of two subscribing witnesses.

FELIX KRAEMER.
